OUTBOARD MOTOR

Romuald Karasinski, Waukegan, Ill., assignor to
 Johnson Motor Company, Waukegan, Ill., a
 corporation of Delaware

Refiled for abandoned application Serial No.
 722,721, April 27, 1934. This application De-
 cember 23, 1935, Serial No. 55,870

5 Claims. (Cl. 115—17)

This invention relates in general to an outboard motor and has more particular reference to a retarding or trolling plate used in connection with a motor-boat for operating it at a low rate of speed.

Although an outboard motor may be operated at different speeds to propel a boat correspondingly, it is often desirable to operate the boat at a very low rate of speed, as for fishing or trolling, and a principal object of the present invention is to produce a simple and inexpensive device which is attached to the outboard motor for operating it and a boat to which it is connected at a low rate of speed.

Another object of the invention is in the provision of a movable trolling plate which is automatic in its action, depending upon the force exerted by the propeller to raise it from trolling position.

A further object of the invention is in the provision of a trolling plate which is adapted for use in connection with outboard motors having an underwater exhaust.

A still further object of the invention is in the provision of a trolling plate which has curved portions for producing greater rigidity and for stabilizing the motor in its use while running.

Other objects of the invention will appear hereinafter, the preferred construction being illustrated in the accompanying drawing.

In the drawing, Fig. 1 is a side elevation of the lower driving unit and propeller of an outboard motor driving unit to which the present invention is applied;

Fig. 2 is a plan view of the trolling plate; and Fig. 3 is a section taken on the line 3—3 of Fig. 2.

Trolling plates of various kinds have been used with boats and also with outboard motors but the present one is attached directly at the rear of an anti-cavitation plate which is formed integral with the lower driving casing of an outboard motor and provision is made for discharging the underwater exhaust from the motor through the upper edge of the trolling plate when it is in a retarding position for otherwise the exhaust discharge would be nearly closed and the exhaust gases would be directed toward the propeller thereby tending to produce slippage and racing of the motor.

Referring now more particularly to the drawing, a lower drive unit only of an outboard motor is shown in Fig. 1 having a smooth walled casing 5 above and below an anti-cavitation plate 6. A lower enlarged portion 7 for seating the

driving mechanism (not shown) for a propeller 8 disposed below and toward the rear of the anti-cavitation plate 6 and having portions arching the upper edge of the path of travel of the propeller blades and providing an inlet 9 at the rear of the propeller for receiving water thrust rearwardly thereby and a discharge opening 10 in advance of the propeller to withdraw water from a passage within the casing thereby causing a circulation of cooling water to the engine, 10 which, however, forms no part of the present invention.

Also within the casing 5 and at the rear thereof is an exhaust passage 11 which extends through the rear of the anti-cavitation plate 6 15 and has a discharge opening 12 below the anti-cavitation plate and in the propeller race for discharging the exhaust gases from the engine at the rear of the motor and below water level.

The above construction is common with 20 motors of this type with the exception that the anti-cavitation plate 6 terminates closely adjacent the rear edge of the casing in a pair of spaced ears 13 and a trolling plate 14 has corresponding ears 15 through which a hinge rod 16 25 is inserted with a spring 17 mounted on the rod between the ears 13 and having oppositely extending extremities 18 engaging the plate 14 and the plate 6 and tending to turn the trolling plate 14 downwardly to the position shown in 30 Fig. 1. The trolling plate is provided with projections 19 for engaging the underside of the anti-cavitation plate 6 and limiting the downward movement of the trolling plate 14 so that it will be clear of engagement with the propeller 8.

In the central upper portion of the trolling plate 14 is an opening 20 located directly back of the opening 12 for the exhaust gases so that even when the plate is in the downward position as shown in Fig. 1, the exhaust gases are discharged, freely into the water below the anti-cavitation plate 6. This opening 20 is of greater extent than the actual discharge opening 12 so that even if the trolling plate 14 is in an inclined position, ample opening will be afforded through the plate 14 for the discharge of the exhaust gases therethrough.

It is important that the trolling plate be both 50 light and strong and it is preferably formed or cast in a thin sheet with curved portions 21 extending outwardly from the center and facing downwardly or inwardly toward the motor casing when in a lowered position so that the trolling plate will have a tendency to stabilize the motor 55

in its movement through the water, the curved portions also tending to guide the water from the propeller outwardly from the trolling plate when it is in lowermost position.

5 This trolling plate is automatic in operation, dependent upon the pressure of the spring 17 and the driving power of the propeller. With a proper spring tension the trolling plate will be forced downwardly until the stops 19 engage the 10 underside of the anti-cavitation plate when the propeller 8 is being driven at slow speed. When the speed, and consequently the power of the propeller, is increased, the tension of the spring 17 will be overcome and the trolling plate 14 will be raised depending upon the power of the propeller until the trolling plate may reach a position in which it is substantially parallel or forms a substantial continuation of the anti-cavitation plate 6 as represented in the broken outline as shown 15 in Fig. 1. Thus the action of the trolling plate is entirely automatic and no manual attention need be given thereto while it is in operation. To operate the plate for trolling, the speed of the engine is simply cut down, whereupon the spring 17 turns the trolling plate downwardly and if the operator of the motor wishes to drive the boat more rapidly he simply speeds up the engine, which increases the driving power and raises the trolling plate in accordance therewith. The trolling plate thus retards the boat or augments the function of the anti-cavitation plate 6.

This application is a refile of my abandoned application Serial No. 722,721, filed August 27, 1934.

35 I claim:

1. In an outboard driving unit having a casing with an underwater exhaust and a driving propeller, a trolling plate hinged to the casing and movable from a position at the back of the propeller to a position at an angle thereto, the underwater exhaust opening being located adjacent the upper edge of the plate, and the plate having an opening in the upper portion thereof opposite the said discharge opening to admit the exhaust therethrough regardless of the position of the plate.

2. A trolling plate for an underwater exhaust, the plate being provided with means for hinging it to the rear of the unit and having an opening adjacent its upper edge through which the exhaust may pass regardless of the position of the plate.

3. A marine propulsion device comprising the combination with a propeller and a support therefore, of a plate pivoted to said support and provided with stop means limiting its pivotal movement to a range from an upright position im-

mediately behind the propeller to an approximately horizontal position immediately above the propeller slip stream, said plate being freely oscillatable within said range, and means supplementing the action of gravity on said plate for biasing said plate toward its said upright position, said plate being substantially symmetrical and centered behind said propeller, whereby in its upright position it will intercept the propeller slip stream without materially affecting the course of a craft propelled.

4. A marine propulsion device comprising the combination with a propeller and a support therefore, of a plate having means pivotally connecting it with said support and providing for the free movement of said plate through a range from a substantially upright position immediately behind the propeller to a second position substantially parallel to the propeller slip stream, stops limiting the movement of said plate beyond said first position, and a spring biasing said plate for movement toward said first position, said plate being subject to the action of propeller slip stream thrust in opposition to said spring for thrust responsive movement about its fulcrum in said range, the strength of said spring being predetermined with reference to the thrust exercised by the propeller slip stream at low and high propeller speeds in a relation such that the spring will overcome the propeller slip stream thrust at low propeller speeds and maintain said plate in said upright position, and the propeller slip stream thrust will overcome the spring at higher propeller speeds and force said plate toward its second position.

5. A marine propulsion device comprising the combination with a propeller and a support, of a horizontal pintle connected with the support above the propeller, a plate fulcrumed upon the pintle and having its lower portion movable across the propeller slip stream to a substantially upright first position, said plate being also freely movable about said pintle to a substantially horizontal position in which said position is outside of the propeller slip stream, and a spring biasing said plate for movement toward said first position and sufficiently strong to overcome the action of the propeller slip stream upon said plate at low propeller speeds, said spring being sufficiently light in its pressure upon said plate to permit said plate to yield to the thrust of the propeller slip stream as the speed of the propeller is increased and to remain completely out of said propeller slip stream throughout a substantial range of cruising speeds of the propeller.
